CLAIM

I claim the ornamental design for a combined refrigerated bar and television cabinet, as shown and described.

DESCRIPTION

FIG. 1 is a top, front perspective view of the combined refrigerated bar and television cabinet shown in a retracted position, showing my new design;

FIG. 2 is a bottom, rear perspective view thereof;

FIG. 3 is a front view thereof;

FIG. 4 is a rear thereof;

FIG. 5 is a right side thereof;

FIG. 6 is a left side thereof;

FIG. 7 is a top view thereof;

FIG. 8 is a bottom view thereof;

FIG. 9 is a top, front perspective view of the combined refrigerated bar and television cabinet shown in an extended position;

FIG. 10 is a bottom, rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines show portions of the article that form no part of the claimed design.

1 Claim, 12 Drawing Sheets
